UNITED STATES PATENT OFFICE.

NORBERT J. C. LESTER, OF KNOXVILLE, TENNESSEE.

TIMER.

Application filed July 5, 1923. Serial No. 649,616.

To all whom it may concern:

Be it known that I, NORBERT J. C. LESTER, a citizen of the United States, and resident of Knoxville, in the county of Knox and State of Tennessee, have invented certain new and useful Improvements in Timers, of which the following is a specification.

My invention relates to timers or commutators for controlling the ignition in multiple cylinder internal combustion engines, and is illustrated as applied to a Ford car, although the principles of the invention may be used in other relations.

An object of the invention is to construct a timer that will be simple in construction and efficient in operation and that can be substituted for the timer on Ford cars without any change in the machine.

Another object of the invention is the provision of contact plates and brush so related that perfect contact will always be made.

Another object is the provision of a key for fastening the brush to the usual cam shaft so as to permit sliding movement of the brush but to cause it to rotate with the shaft in any position of longitudinal adjustment.

Other objects will be apparent from the following detailed description and the appended claims.

In the drawings:

Figure 1 is a front view of the cap or shell.

Figure 2 is a rear view of the same showing the contact plates and the brush, with the cam shaft in section.

Figure 3 is a side elevation with the shell and contact carrying ring in section.

Figure 4 is a view showing the relation of the cam shaft, spring, key and brush.

The shell 1 of the timer is preferably formed of thin steel or similar metal and has four holes 2 in its periphery which are substantially equally spaced. At the front there is a strip 3 preferably integral with the shell and having a general V shape. It is provided with a central depression 4 with which contacts the usual flat spring C of the Ford structure to hold the timer in position. It also has a projection 5 at one side having a short tubular member 6 to receive the usual rod which extends from the steering rod to the timer and is operated to advance and retard the spark. The shell is slightly bent in around its front edge 7 for a purpose hereinafter apparent.

Fitting within the shell is an insulating ring 8 which is made of red fibre or any suitable insulating material, and it is intended to fit snugly in the timer shell or cap. Depressions are formed in its face in which are set four contact plates 9. A central opening 10 in the insulating ring 8 forms the inner boundary of the contact plates 9, their sides are radii extending from the center of the ring, and their outer boundaries are arcs of a circle also struck from said center. The four contact plates are separated from each other by insulating portions of exactly the same shape and size as the plates. All edges of contact plates are cut at right angles to the surface of the ring 8, but may be beveled.

A bolt 11 screws from the front of the insulating ring through it into the contact plate, and is held in position by a lock nut 12. A knurled nut 13 screws on each bolt to hold the proper timer wire in place, acting as a binding post. The outer edge of the insulating ring 8 is beveled slightly at 14 and fits against the bent edge of the shell to keep the ring from passing through the shell. Small pins or nails 15 are then driven in the ring just outside of the shell and these prevent withdrawal of the ring from the shell in the opposite direction.

The drawings show the usual cam shaft A and large timer gear B, and the brush 16, shown detached in Figure 4, is adapted to fit over the end of the cam shaft A. The opening in the brush tapers slightly, being larger at the rear as shown in Figure 3, and the front end is cut perpendicular to the axis, while the rear end is sloped off as shown at 17 to the ledge 18 which is really an extension of one side of the cylindrical portion of the brush. This ledge 18 has a projecting L-shaped member 19 having a front face 20 forming the contact portion and adapted to contact with the contact portions 9 carried by the insulating ring 8.

A keyway 21 is provided in the cylindrical portion of the brush and is adapted to coact with the flattened central portion 22 of a key 23 which has its longer leg 24 adapted to fit in a hole 25 in the cam shaft A, and its shorter leg 26 fits over the end 27 of the shaft in order to position it properly while the brush is being placed on the shaft.

A spring 28 encircles the shaft A having one end bearing against a shoulder 29 on the shaft and the other end against a shoul-

- der 30 formed on the brush by the intersection of the sloping portion 17 with the flat face of the extension 18. The spring serves to yieldingly hold the contact face 20 of the brush against the insulating ring. Since the spring contacts with the brush with greater pressure at the shoulder 30 which is on the side next to the contact member 19 of the brush than at any other point, and since the opening in the brush which fits over the cam shaft is somewhat larger at the rear, it will be seen that the spring will hold the contact face 20 firmly against the contact portions 9 of the ring 8.
- 15 The inner edge of the front end of the brush is slightly chamfered at 31 to prevent engagement of the brush with the screw threads on the shaft. It will be noted that the hole in the center of the insulating ring 8 is large enough so that the shaft and brush can rotate therein without any contact with the ring 8. The brush is preferably made of a single piece of brass, although the invention is not limited thereto.
- 20 The method of assembly and operation of the device will be apparent from the above description and need not be repeated. It will be noted that the device consists of few parts which are easily assembled and can 30 be substituted for the ordinary Ford timer without any change in the construction of the car. It will be understood that the exact form and materials may be varied and that the device may be adapted for use in different relations on other internal combustion engines without departing from the spirit of the invention. In general it may be stated that the invention is limited only by the scope of the appended claims.
- 35 40 I claim as my invention:
1. A timer comprising a shell, a ring of insulating material fitting within said shell, contact members therein lying flush with the face of the ring, a brush member having a slightly tapering opening fitting over an operating shaft, means for holding the brush against rotation relative to the shaft but permitting relative longitudinal movement,
  2. A timer comprising a shell, a ring of insulating material fitting within the shell, contact members carried thereby, a brush having a slightly tapered central opening fitting over an operating shaft, means for causing the brush to rotate with the shaft but permitting endwise and rocking motion thereon, and means engaging said brush to give it both movements thereby holding it in close engagement with said contact members.
  3. A timer comprising a shell, a ring of insulating material fitting within said shell, contact members carried thereby, a brush having an opening fitting over an operating shaft, a U-shaped key having one leg fitting in an opening in the shaft, a shorter leg engaging the end of the shaft, and a connecting portion shaped to engage a key way in the brush.
  4. A timer comprising a series of stationary spaced contact members, a brush having an opening to fit over an operating shaft, a U-shaped key having a leg fitting in an opening in the shaft, another leg engaging the end of the shaft, and a flattened connecting portion to engage a key way in the brush, and a spring adapted to press the brush into contact with said contact members.
  5. A timer comprising a series of stationary spaced contact members, a brush having a tapering central opening adapted to fit over an operating shaft and rock slightly thereon, a projecting contact member at one side of the brush, means for causing the brush to rotate with the shaft, and a spring for moving said brush longitudinally and rocking the same to hold the contact member in engagement with the stationary members.

In testimony whereof I have hereunto subscribed my name.

NORBERT J. C. LESTER.
